UNITED STATES PATENT OFFICE.

GEORGE K. HENDERSON, OF INDIANAPOLIS, INDIANA, ASSIGNOR TO INTERNATIONAL PRINTING COMPANY, OF INDIANAPOLIS, INDIANA, A CORPORATION.

CARTON SEALER.

Application filed June 20, 1925. Serial No. 38,458.

To all whom it may concern:

Be it known that I, GEORGE K. HENDERSON, a citizen of the United States, and a resident of Indianapolis, county of Marion, 5 and State of Indiana, have invented a certain new and useful Carton Sealer; and I do hereby declare that the following is a full, clear, and exact description thereof, reference being had to the accompanying drawings, in which like numerals refer to like parts.

This invention relates to a carton or box sealing machine of a semi-automatic type wherein the knockdown cartons or boxes are 15 placed on forms and their end and side flaps sealed by clamping them down after adhesive material has been applied, and holding them in clamped position until the adhesion is complete.

20 The main object of the invention is to improve upon the machine disclosed in Letters Patent No. 1,424,018 issued July 25th, 1922, whereby provision is made for simultaneously operating upon and sealing both ends 25 of the box or carton, and provide means for carrying or supporting the upper rollers, as well as exerting a clamping pressure through the lower rollers.

30 The full nature of the invention will be understood from the accompanying drawings and the following description and claims.

35 Fig. 1 is a perspective view of the machine looking toward the front thereof with all of the clamps in sealing position. Fig. 2 is the same as Fig. 1 with one set of clamps in open position. Fig. 3 is a top plan view. Fig. 4 is a perspective view looking toward the bottom.

40 In the drawings there is shown a box clamping device comprising a pedestal 10 having an upwardly extending shaft 11 upon which the table 12 is rotatably mounted. Fixedly mounted or keyed to said shaft, 45 there is a cam track 13 below the table and a cam track 14 above the table. Therefore said table is rotatable with respect to the two cam tracks through the medium of the radial handles 15 which are secured thereto. Supported about the periphery of the table there 50 are a plurality of upright blocks 16 which are clamped to upright supports 17 through the medium of the screws 18. Said supports 17 are rigidly secured to the periphery 55 of the table and braced thereon by the brack-

ets 19. The forming blocks 16 extend below as well as above the surface of the table. The boxes 20 are mounted over the blocks 16 so that their flaps are folded down in the desired position for sealing after suitable adhesive has been applied.

60 Hingedly mounted on each end of the block 16 there are upper clamping plates 21 and lower clamping plates 22, said clamping plates being secured to the arms 23 and 24 65 respectively. On the front portion of the upper plates 21 there are suitable weights 25, and on the under surface of both plates 21 and 22 there are suitable pads 26, the pads directly engaging the flaps of the box or 70 carton to be sealed. The weights 25 act, through gravity, to bring the upper plate 21 in sealing position when the rollers 29 engage the track 14 to apply the pressure required in a positive manner.

75 For moving the upper plates 21 in and out of clamping position, the cam track 14 is cut away as shown in Figs. 1 and 3 at the forward portion, and within said cutaway portion there is a downwardly extending 80 projecting flange or cam member 27. On one side thereof there is a second outwardly projecting trip cam member 28.

85 As the table is rotated by the operator through the medium of the handles 11, the upper plates 21 are maintained in clamping position through the medium of the weights 25 and engagement of the rollers 29, with the track 14. They continue in this position during the rotation of the table until the respective rollers reach the position where the track is broken as indicated at 30 in Fig. 3. By reason of the inclined face of cam 27 engaging the rollers 29 overcoming the weight 90 25, the roller drops through the opening in the track and engages the downwardly extending cam 27 so as to be forced to a vertical position as illustrated at the top of Fig. 3. This relieves the box so far as the upper 95 end is concerned, whereby the operator may remove it and replace it with another box to be sealed. The further rotation of the table brings the roller 29, which is in lowered position, into engagement with the inner surface of the cam 28. Its continued movement 100 causes it to be lifted back up on the track whereby, assisted by the weight 25, it will be caused to resume its clamping position. This position it will maintain for permitting 105 the adhesive on the box to take effect until it 110

again reaches the break in the track indicated at 30.

With respect to the lower clamping plates as illustrated in Fig. 4, the track 13 is so formed as to cause the rollers 31, mounted on the arms 24, to exert an upward pressure against the lower end of the box through the clamping plate 22. This clamping pressure is exerted during the rotation of the table, until the rollers 31 reach the break in the track indicated at 32. The weight of the clamping plate, overcoming that of the roller drops down away from the box, and roller passes up into the break in said track as shown in Figs. 2 and 4. As the break in the tracks 13 and 14 are positioned on the same side of the machine, the ends of the carton will be simultaneously relieved so as to permit the operator to remove the sealed box and replace a new box to be sealed while both clamping plates are in released position.

Thus, both ends of the carton may be simultaneously operated upon, rather than a single end as heretofore.

The invention claimed is:

1. A sealing machine for paper receptacles having means for supporting a receptacle adjacent both ends thereof, means for clamping and sealing the top of said receptacle under pressure, means for clamping and sealing the bottom thereof under pressure, and separate means for actuating said top and bottom means simultaneously for causing the same to automatically release said receptacle.

2. A sealing machine for paper receptacles having means for supporting a receptacle adjacent both ends thereof, means for clamping and sealing the top of said receptacle under pressure, means for clamping and sealing the bottom thereof under pressure, separate means for actuating said top and bottom means simultaneously for causing the same to automatically release said receptacle, and means for thereafter causing said top and bottom sealing means to be automatically brought back to operative position.

3. A sealing machine for paper receptacles having means for supporting a receptacle adjacent each end thereof, means for clamping and sealing the top of said receptacle under pressure, means for clamping and sealing the bottom thereof under pressure, a cam member for maintaining said bottom sealing means in clamping position through engagement therewith and having a cut-away portion for permitting the release thereof, and a separate member for engaging the top sealing means for releasing it from engaging position simultaneously with the release of the bottom sealing means.

4. A sealing machine for paper receptacles having a supporting member and cam mem-

bers mounted on each side thereof, said supporting member and cam members being rotatable relative to each other, means for supporting a receptacle to be sealed adjacent each end thereof on said supporting means, top clamping plates pivotally mounted on said supporting means, lower clamping plates pivotally mounted thereon, and means associated with said cam members for actuating said clamping plate, whereby they will be simultaneously released from both ends of the receptacle when said members are brought to a given position relative to each other, and on further relative movement thereof will cause said clamping plates to be brought into clamping position.

5. A sealing machine for paper receptacles having a supporting member for supporting said receptacle adjacent each end thereof, an upper track having a cutaway portion, a cam positioned in said cutaway portion, a second cam member associated therewith, a lower track member having a cutaway portion, said track members and supporting member being rotatable relative to each other, upper clamping plates adapted to be actuated by said upper track, and lower clamping plates adapted to be actuated by said lower track member, whereby upon relative rotation of said members said upper and lower clamping plates will be simultaneously released and thereafter simultaneously brought into clamping position.

6. A sealing machine for paper receptacles having a supporting member for supporting the receptacle to be formed at each end thereof, clamping plates positioned adjacent the upper and lower ends of said receptacles so as to engage and clamp the ends thereof cam-like members mounted on said machine, and means adapted upon the relative rotation of said supporting members and cam members with respect to each other to engage said cam members and simultaneously open said clamping plates with respect to said receptacle for permitting its removal and replacement, and thereafter bring said clamping plates into engaging and clamping position.

7. A sealing machine for paper receptacles comprising upper and lower stationary tracks, said tracks being provided with cut-away portions on each side of said machine, a supporting table rotatably mounted between said tracks, a receptacle supporting form mounted on said table, upper clamping plates hingedly mounted on said forms in position to engage and clamp the tops of said receptacles, lower clamping plates hingedly mounted on the bottom of said forms for engaging and clamping the bottoms of said receptacle, and means mounted on said clamping plates in position to be engaged by the respective tracks for hold-

ing said clamping plates in clamping position and permitting the release thereof when said means are moved to the cutaway portion of said tracks.

- 5 8. A sealing machine for paper receptacles comprising upper and lower stationary tracks, said tracks being provided with cutaway portions on each side of said machine, a supporting table rotatably mounted between said tracks, a receptacle supporting form mounted on said table, upper clamping plates hingedly mounted on said forms in position to engage and clamp the tops of
- 10

said receptacles, lower clamping plates hingedly mounted on the bottom of said forms for engaging and clamping the bottoms of said receptacles, and rollers mounted on said clamping plates adapted to ride on said tracks for holding the clamping plates in clamping position and simultaneously releasing the same upon reaching the cutaway portion thereof. ¹⁵

20 In witness whereof, I have hereunto affixed my signature.

GEORGE K. HENDERSON.
